BESSEMER CONVERTER

Reed Lewis, Pittsburgh, Pa., assignor to Crucible
Steel Corporation of America, New York, N. Y.,
a corporation of New Jersey

Application May 17, 1951, Serial No. 226,815

13 Claims. (Cl. 266—36)

1

This invention pertains to improvements in bessemer converters and bessemerizing processes.

A primary object of the invention is to provide a bessemer converter of novel construction wherein molten ferrous metal may be subjected to both the acid and basic bessemerizing processes, or vice versa, in successive stages without removing the molten metal from this single converter.

A further object is to provide a novel process employing a converter of the type aforesaid according to which an impure grade of ferrous metal, such as pig iron from the blast furnace, is first subjected to an acid bessemerizing blow, following which the acid slag is poured off, and the metal thereupon subjected to a basic bessemerizing operation in the presence of a basic slag.

In accordance with the fundamental precepts of the invention the aforesaid results are achieved with a side-blow type of bessemer converter consisting in its essentials of a converter vessel of generally closed, hollow configuration, having a single outlet port formed therein for escape of combustion products and through which the "blow" takes place. This vessel which may be of spherical, ovoid, cylindrical, or other suitable configuration, is in general so shaped as to provide a pair of hearths disposed respectively on opposite sides of said port. One of these hearths is provided with a refractory lining of a high-melting, acid or siliceous material, such as ganister, while the opposite hearth is lined with a high melting basic material such as dolomite. These acid and basic linings are terminated sufficiently apart on opposite sides of said port as to provide an intermediate zone, including said port, which is lined with a high melting refractory material of neutral characteristics such as chromite, and which serves to separate the acid and basic linings from each other. The vessel is mounted for rotation about an axis substantially perpendicular to the axis of the port, whereby rotation to one position will cause a charge of molten iron deposited therein, to flow by gravity into the acid lined hearth, whereas rotation to the diametrically opposite position will cause the metal to flow into the basic lined hearth. It will be understood of course, that in thus causing the metal to flow from the acid-lined to the basic-lined hearth, or vice versa, the direction of rotation must be such as to prevent discharge of the metal from the open or "blow" port above mentioned. That is the port must be

5 swung from one horizontal position, upwardly to the oppositely disposed horizontal position. For introducing an air blast into the converter for effecting the blow, tuyères may be formed in the vessel walls on opposite sides of and in substantial alignment with the outlet port; or, alternatively, may be insertable through the outlet port or through suitable openings adjacent thereto. In either case the air blast is applied 10 to the tuyères through suitable manifolds or headers as explained below.

As stated the converter is of the side-blow type, the blow being effected with the port horizontally disposed, or approximately so, pointing 15 in one direction or the opposite depending on whether the bessemerizing is being carried out in the acid or in the basic hearth. The tuyères may be so disposed that a portion of the air blast may be injected onto or below the metal surface while the remaining portion is directed substantially parallel to the metal surface and into the gaseous combustion products.

20 In operation the furnace is rotated to a position such that the port is pointed upwardly in a vertical or suitably inclined position and a charge of molten ferrous metal, of an inferior or impure grade, such as pig iron, poured therein. The furnace is thereupon rotated to a position such that the metal charge flows onto the acid hearth. Ordinarily no slag is added, although some iron oxide, such as Fe_3O_4 , may be added at this point for purposes of assisting in the oxidation of the impurities and in the formation of the slag. The blow is then started by applying an air blast to the tuyères. During 25 the blow the major portion of the silicon and some of the manganese and carbon are oxidized to silica, manganese oxide and carbon monoxide respectively. Also some of the carbon monoxide 30 may be oxidized to carbon dioxide, as may be required for metal or slag temperature control. This oxidizing process results in the formation of an acid or siliceous slag which floats on the surface of the molten metal. At the end of the blow the air blast is turned off and substantially 35 all of the slag is poured off by rotating the furnace until the port is pointed to a suitable downwardly inclined position.

40 Thereupon the furnace is rotated in the opposite direction until the molten metal flows onto the basic hearth. Lime (CaO) with a slag thinner, such as fluospar (CaF_2), if the latter is needed for fluidity of the slag, is then charged onto the surface of the metal, and the air blast 45 again turned on, and the blow again started.

The remainder of the silicon, manganese and carbon are thus removed from the metal bath to the extent desired, the carbon monoxide thus produced being further oxidized to CO_2 to the extent required to give the resulting steel a proper pouring temperature. The phosphorous present is oxidized to P_2O_5 , and is, in this form, taken up by the basic slag.

The air blast is again turned off and the converter rotated sufficiently to pour off the slag through the blow port. Thereupon the furnace is further rotated to discharge the steel into a ladle, for further processing in the open hearth or electric furnace or for teeming into ingots.

As an alternative to the aforesaid process, if low temperature hot metal is charged into the converter, the blow can be started in the basic section. Phosphorous is thus eliminated to the extent required, first blowing with a basic slag as aforesaid, which is then poured off, and the metal thereupon transferred to the acid side of the converter for elimination of the other metalloids. A portion of the silicon present in the initial charge may be oxidized while the metal is in the basic section to furnish that required for basic slag formation.

In the converter construction described, the purpose of interposing the zone of neutral or chrome lining between the acid and basic lined portions is to prevent the latter from contacting and hence interacting with one another. If the acid and basic linings were in contact they would combine chemically to give a lower melting point silicate material, thereby producing a zone of contact subject to extremely rapid erosion or "washing." Accordingly for satisfactory operation and acceptably long life, it is necessary that the acid and basic linings be separated by a neutral lining, such as chromite, which does not combine or react with either the acid or basic linings, and which prevents the latter from reacting or combining with each other.

It is also essential to successful operation of the converter that refractory materials be employed for the various linings which have high melting points, i. e. melting points well above that of the molten metal bath, as otherwise the linings will fail so rapidly as to be worthless from a practical operating standpoint. The average temperature of the metal bath during the acid blow is about 2910° F. and for the basic blow, about 2980° F. Since canister (acid), magnesite and dolomite (basic) and chromite (neutral) have melting points of about 3100° , 5072° , 4000° and 4127° F. , respectively, all well above the aforesaid temperatures of the molten metal bath, they are preferred materials for the acid, basic and neutral lined portions aforesaid of the converter.

Having thus described in its essentials, the novel bessemer converter of the invention and the novel processes herein for employing the same, reference will now be had, for a more detailed description, to the accompanying drawings, wherein:

Figure 1 is a longitudinal sectional elevation of a cylindrical converter in accordance with a preferred modification of the invention; while Figures 2 to 6 inc. are respectively sections at 2-2 to 6-6 inc. of Fig. 1, Figs. 3 to 6 inc. being fragmentary views sufficiently illustrative of the structural details shown.

Figure 7 is a transverse sectional elevation through another modification of a cylindrical converter in accordance with the invention, as

taken at 7-7 on the schematic plan view thereof, Fig. 7a. Figure 8 is a longitudinal sectional elevation as taken at 8-8 of Fig. 7. Figure 9 is a staggered line sectional elevation as taken at 9-9 of Fig. 7. Figure 10 is a fragmentary right hand plan view of the manifold shown in Fig. 9. Figure 11 is an enlarged fragmentary section taken at 11-11 of Fig. 8; while Figure 12 is an enlarged fragmentary section taken at 12-12 of Fig. 9. Figures 13 and 14 are respectively fragmentary sectional views taken at 13-13 and 14-14 of Fig. 11. Figure 15 is a detail in elevation and partly in section of one of the tuyère nozzles.

Figures 16 and 17 are more or less diagrammatic sectional showings of a further modification of a generally cylindrical type of converter in accordance with the invention, having an oval or elliptical configuration in transverse section, Fig. 16 being a transverse sectional elevation as taken at 16-16 of Fig. 17, and Fig. 17 being a longitudinal sectional elevation as taken at 17-17 of Fig. 16. Fig. 18 is a more or less schematic showing of a still further modification, the tuyères of which are insertable through the blow port and are independently adjustable in inclination with respect to the molten bath, this view being a transverse sectional elevation corresponding to Fig. 7.

Referring to Figs. 1 to 6 inc., the converter shown therein comprises an outer steel shell 10 of cylindrical configuration, made up of plane and circular end walls 11, 12, and a cylindrical body 13, welded or otherwise secured together as shown. The body 13 has formed therein a slot-like rectangular opening extending longitudinally substantially the entire length thereof as outlined by the dashed rectangle 14-17 inc., Fig. 2, and as shown in transverse section at 15, 17, Fig. 2. As shown most clearly in Fig. 2, the shell on one side of said opening, is lined, as at 18, with an acid or siliceous refractory material, such as ganister, and is lined on the opposite side of said opening, as at 19, with a basic refractory material, such as magnesite or dolomite. The acid and basic lined portions are thus spaced apart by an intermediate zone, which is lined, as at 20, with a neutral material, such as chromite.

The slot-like opening 14-17 formed in the outer shell has inserted therein, a removable plug 21 of neutral refractory material. This plug is chamfered or beveled on all sides, as at 22, 23, Figs. 1 and 4, to provide in effect a wedge like construction tapering inwardly on all four sides from its outer to its inner dimensions, in the manner illustrated in section in Fig. 4, in order to wedge the plug lining in place with the contiguous converter lining, and the lining of the plug is further wedged in place by a grouting of clay or the like, as at 23.

Also, referring to Fig. 4, the plug is held in place by means of steel plates; such as 21a, which are welded to the outer steel shell 13a, of the plug, and which with the plug inserted, as shown, overlap or overlie the contiguous portions of the outer converter shell 13, in the manner shown at 13b. The underlying portions of the converter shell have secured thereto at spaced intervals, a series of upstanding studs, as at 21c, each of the studs being transversely slotted, as at 21d, for reception of locking wedges, such as 21e, which are driven through the slots thus to wedgily lock the plug 21 in place against the converter shell in the manner illustrated. With this arrangement the plug 21 may be quickly removed by

merely knocking out the wedges, thereby facilitating rapid and economical renewal of this portion of the lining, which is the portion most rapidly eroded.

The plug 21 has centrally formed therein a port 24, Fig. 2, for escape of combustion gases and comprises the outlet for the "blow." This port is also used for charging and pouring. On each side of port 24, the plug 21 has formed therein a series of tuyères, as at 24 to 28 inc. Certain of these tuyères, 25, are inclined toward the acid-lined portion 18, for directing an air blast onto the surface of the molten metal during bessemerization in the acid-lined portion or hearth. Certain other tuyères 28 are inclined toward the basic-lined portion 19, for similarly directing an air blast onto the metal surface during bessemerization in the basic hearth. The remaining tuyères 26, 27 are parallel to the axis of the port 24 for directing air blasts into the gaseous products of combustion produced by the blow.

It is important that the plug 21 which includes the tuyère openings and "blow" outlet as above described, be easily removed and renewed in the manner above explained, because the area of most rapid lining erosion in a converter is that adjacent to and including the tuyère openings, slag line and port through which the hot gases blow. The inclusion of the tuyères openings and "blow" port in this easily removable plug, is, therefore, a feature of considerable utility, since it permits the lining in these regions to be easily and quickly renewed without disturbing the remainder of the converter lining.

It will be observed that all of the tuyères 25-28 inc. enter the converter well within the confines of the pouring lips 29, 30, of the port 24, thus permitting the pouring off of slag and molten metal without causing flow thereof into the tuyères. By reason of this construction the air blast may be shut off during the pouring, or during the blow, the latter in contrast to conventional bottom blow converters wherein this cannot be done. The port 24 may be of any suitable aperture, rectangular, circular, oval, etc., and may extend between the tuyères openings, as at 31, for increased blowing aperture.

Referring more particularly to Fig. 4, the tuyères 25 to 28 inc., are supplied with an air blast from headers or manifolds 35 to 38 connected thereto respectively. Headers 35 and 36, preferably comprise concentric tubes, disposed one within the other; and the same applies to headers 37 and 38. These header pairs 35, 36 and 37, 38, are preferably mounted in refractory housings 39, 40, which in turn are mounted upon and extend longitudinally along the outer steel shell 13a of the converter plug 21. As shown in Figs. 1 and 3, the headers 35-38 inc., project beyond one end of the converter, being individually connected thereto to couplings 41-44 inc., respectively. These couplings serve rotatively to connect the headers with concentric air blast supply pipes 46 and 47, which are coaxial with the converter. Thus couplings 41 and 43 terminate in a cap-like member 45 into which the terminus of supply pipe 46 is journaled; while couplings 42 and 44 terminate in a collar-like bearing into which the terminus of supply line 47 is journaled. These supply line termini are provided with sidewall openings, as at 49 and 50, which register with one or the other of the oppositely disposed couplings 41, 43 and 42, 44, when the converter has been rotated to one or the other of its oppositely disposed blowing positions as explained below. The cap member 45 is welded to collar 48, as at 51, and the

entire assembly is carried by a stationary support 52. Feeder pipes 53, 54 are coupled to pipes 46, 47 respectively, through disconnectable couplings, as at 54a.

5 The furnace is supported at its flanged ends 55, 56 on a series of rollers, as at 57, the latter being journaled to fixed bearing housings, not shown for simplicity, and being of conventional construction. For rotating the furnace, a ring 10 gear 58 is secured to the end plate 11, which meshes with a pinion 59, keyed to the shaft of a reversible drive electrical motor.

As shown in Fig. 2, with the converter rotated to a position such that the blow port 24 points horizontally to the right, a charge of molten metal, such as 60, will lie in the basic-lined section; whereas if the furnace is rotated 180° counterclockwise the charge will flow onto the acid hearth, and the port 24 will point horizontally to the left.

20 **zontally to the left.** Stacks, such as **61, 62**, may be optionally pro-
21 vided which register, respectively, with the con-
22 verter port **24**, when the latter is rotated to one
23 or the other of the two blowing positions above
24 mentioned. To facilitate pouring or repairs, the
lower portion **63, 64** of these stacks may be made

lower portion **63**, **64** of these stacks may be made separate from the upper portion, and displaceably mounted on trucks, as at **65**, **66**, running on tracks, as at **67**. The upper portions of the stacks are of course stationarily mounted in a conventional fashion.

For charging purposes, a charging hopper 68 may be so mounted above the converter as to register with the port 24 when the latter is rotated by the converter to point vertically upward. Alternatively the metal may be poured in through a trough when port 24 is rotated to point approximately in a horizontal direction. Also the converter may be made of split construction as indicated at 69, 70, for purposes of relining and repair.

45 Referring to Figs. 7 to 15 inc., the converter shown therein embodies generally the same construction and mode of operation as that above described except for the tuyère arrangement employed for supplying the air blast. The converter proper will, therefore, be but briefly described, attention being concentrated on the tuyère construction and operation.

50 As before, the converter proper comprises an outer steel shell or housing 100, having formed therein a slot-like rectangular opening, extending longitudinally substantially the entire length thereof, as outlined by the dashed rectangle 80-83 inc. The outer shell is provided on its interior, as before, with acid and basic linings 104 and 105, disposed respectively, on opposite sides of said rectangular opening 80-83 inc., these linings being separated by an intermediate zone provided

55

60 with a neutral lining 106. The slot-like opening 80-83 inc., formed in the outer shell, has inserted therein, a removable plug 84 of neutral refractory material. As in the previous converter construction, this plug is chamfered or beveled on 65 all sides, as at 85, 86, to provide in effect a wedge-like construction, tapering inwardly on all four sides from its outer to its inner dimensions, in the manner illustrated most clearly in Fig. 7, in order to wedge the plug lining in place with the

70 contiguous converter lining. And the lining of the plug is further wedged in place by a grouting of clay or the like, as at 87. This plug 84 is removably held in place, in the identical manner described with reference to the previous construction, as by means of plates, studs and

wedges, as illustrated at 21a to 21e inc., Fig. 4, of the previous construction. The plug 84, has centrally formed therein, a port 101 for charging, pouring and escape of combustion products during the blow, and has also formed therein, in alignment with the port 101, and disposed on opposite sides thereof, a pair of longitudinally extending, rectangular or slot-like openings 102 or 103, the latter for insertion and withdrawal of the tuyères as explained below.

The housing 100 is encircled at its opposite extremities by peripherally extending flanges 107, 108, secured thereto, and which rotatably mount the converter on rollers, as at 109, 110, the latter being journaled to stationarily mounted journal housings (not shown). For rotating the converter a ring gear 111, secured to one end thereof, meshes with a pinion 112, keyed to a motor shaft 113.

Further in accordance with the construction previously described, the converter may optionally be provided with oppositely disposed stacks 114, 115, registering respectively with the converter port 101 in the oppositely disposed blowing positions. Also a hopper 116 may be provided as shown for charging the molten metal into the converter.

For supplying an air blast to the converter interior, in each of its oppositely disposed blowing positions, rotatable and displaceable tuyère units are arranged on each side of the converter as shown generally at 120, 121. Each of these units comprises a pair of concentric headers, as at 122, 123, extending longitudinally of the furnace, substantially the entire length thereof, as shown in Fig. 9, the outer header of which is rotatably supported at its opposite ends in swivel blocks, as at 124, 125. These swivel blocks in turn are rigidly secured, as at 126, on the platform 127, of trucks, such as 128, 129, individual thereto. These trucks are in turn displaceable along tracks as at 130, 131, for advancing the units 120, 121 toward and away from the converter, in the manner illustrated in Fig. 7 and as explained below.

Each of the outer headers, such as 123, is provided with a series of aligned apertures, through which extend a series of connecting pipes, as at 132, which are threaded into correspondingly aligned apertures of the associated inner header 122. These connecting pipes 132 are also welded to the outer header 123 about apertures referred to, as at 133, Fig. 11. Alternating with the pipe sections 132 is a second series of pipe sections 134, which are threaded into apertures of the outer header 123, in the manner most clearly shown in Fig. 9. At their upper ends, all of these pipe sections, 132, 134, extend into corresponding passageways, such as 135, Fig. 11, formed in a casting 136.

It will be noted that the passageways 135 are bent at an angle to provide substantially horizontally disposed outlets as at 137. Each of these outlets 137 is provided with means indicated at 138 for quickly attaching and detaching the tuyère pipes such as 139 or 140. These tuyères may be provided with refractory tips, as at 140a. It will be observed that the tuyère pipes 139 are bent downwardly at their outer ends, as at 141, for directing an air blast onto the surface of the molten metal bath, such as 142, while the remaining tuyère pipes 140, extend horizontally, for directing an air blast into the combustion gases above the metal bath. The tuyère pipes 139, 140 are connected in alternating sequence with the passageways 137. The tuyère pipes 140

may be thus connected to the inner header 122 over the pipe sections 132, in which case the remaining tuyère pipes 139 will be connected to the pipe sections 134 extending to the outer header 123. In this way the air blasts applied to the two sets of tuyères may be independently controlled.

For supporting the tuyères 139, 140, there may optionally be welded to the upper surface of the casting 136, a sheet steel platform 143, the projecting end of which is bent downwardly at right angles and thence horizontally as at 144, and is appropriately apertured in the vertical portion for slidable reception of the tuyère pipes, in the manner illustrated in Figs. 11 and 13. The platform 143 may optionally be protected by a refractory shield 145 of brick or the like, covering the upper surface of the platform, which shield may also, if desired be terminated adjacent the casting 136 in a vertically extending refractory curtain or closure plug 146.

Referring to Figs. 8 and 9, the tuyères 139, 140, connected to each set of header pipes, 122, 123, are arranged in banks of two each, as shown generally at 147, 148, Fig. 8, in order to straddle the space occupied by the blow port 101, these two banks of tuyères being further so spaced longitudinally as to register with the slotted ports 102, 103, disposed on opposite sides respectively of the blow port 101.

The inner header 122 is supported concentrically within the outer header 123, by means of baffles, such as 149, Fig. 9, disposed at each end thereof, and welded to the inner and outer headers respectively to provide air tight joints. For supplying separately controlled air blasts to the inner and outer headers, a connection such as 150, Figs. 9 and 10, extends to the inner header at each end thereof, and similarly a pipe connection, such as 151 extends to the outer header at each of its opposite ends.

As above explained each header unit and its associated tuyère assembly is rotatively supported at the opposite ends of the outer header in trunnions, such as 124, 125, which in turn are mounted on railway trucks such as 127. Thus each tuyère assembly may be rotated about its header axis, in the manner illustrated by comparison of the units 120, 121, Fig. 7. In addition each tuyère and header assembly may be displaced toward and away from the converter by movement of the trucks, such as 127, 128, along their respective tracks, 131, 130.

For automatically rotating the tuyère assemblies from the position within the converter as shown at 121, Fig. 7, to a position outside of the furnace, as shown at 120, each outer header, such as 123, may be provided integral therewith at its opposite ends, a pair of parallel lever arms, as at 153—154, to the projecting ends of which are secured studs, as at 155, 156, to which are journaled cam rolls, as at 157, 158. These cam rolls are respectively positioned to ride on cam tracks 159, 160, encircling the outer shell 100, of the converter, at its opposite ends, as shown in Fig. 8, and are of the configurations in axial elevation, as shown at 159, Fig. 7.

Thus as the converter is rotated counterclockwise from the position shown in Fig. 7, the tuyère assembly 121 will be automatically withdrawn from the converter by clockwise rotation due to engagement of the cam rolls, such as 157, with the portions, such as 161, of the cam tracks 159, 160. The tuyère assembly will thus assume a position corresponding to that shown for as-

sembly 120. With continued counterclockwise rotation of the converter, the tuyère assembly 121 will remain fixed in the withdrawn position due to the passage of its cam rolls 157 into the circular portion 161 of the cam, which being of constant radius will produce no further clockwise rotation of the lever arms 153, 154. However, such continued counterclockwise rotation of the converter will cause the tuyère assembly 120 to be rotated clockwise, as the cam rolls 164 thereof pass from the circular portion 162 of the cam tracks onto the camming portion 165 thereof. In this way the tuyère assembly 120 is rotated to a position projecting into the converter corresponding to that shown for assembly 121. Conversely subsequent clockwise rotation of the converter will through media above described rotatively withdraw tuyère assembly 120 from the converter and insert assembly 121 therein. Alternatively, manual or other means may be employed for the insertion and removal of these tuyères.

Thus tuyère assembly 121 will be inserted when the converter is in the right hand blowing position of Fig. 2, i. e. with the blow port 101 pointing to the right for bessemerizing the molten metal charge on the acid hearth 105. And similarly the tuyère assembly 120 will be inserted with the converter in the left hand blowing position for bessemerizing the molten metal charge on the basic hearth 104. It will be observed in this connection that when a tuyère assembly such as 121 is thus inserted, the refractory baffles, such as 146, mounted thereon, act as closure members for the slot-like openings, such as 102, 103, through which the tuyères are inserted, thus causing the blow to take place only through the blow port 101.

As an alternative or supplemental means for inserting and withdrawing the tuyère assemblies into and out of the furnace, additional lever arms, such as 166 and 167, Fig. 2, may be secured to the ends of the outer headers, such as 123. As shown in Fig. 2 these lever arms 166, 167, are mounted at an angle to lever arms 153, 164 respectively, and have journaled to their projecting ends, cam rolls, such as 168, 169, which engage cam tracks, such as 170, 171, mounted above the tracks 131, 130, on which the trucks 127, 128, ride. Referring more particularly to tuyère arrangement 121, Fig. 2, it will be noted that the cam tracks 170, parallel the tracks 131, except for the cam track terminus adjacent the converter which bends upwardly and thence downwardly in hook-like fashion. Thus as truck 129 is propelled to the right, cam roll 168 will ride downwardly along the sloping portion 172 of the cam track and onto the horizontal portion, thereby to rotate the tuyère assembly sufficiently clockwise about its header axis, as the assembly is thus withdrawn from the converter, to permit the downwardly inclined tuyère sections 141 to clear the lower ledges of the converter parts 102, 103. Conversely as the truck is subsequently propelled to the left, the cam rolls 168 will ride up the inclined cam track portion 172, thus to rotate the tuyère assembly counterclockwise sufficiently to permit the tuyère sections 140, 141 to enter the ports 102, 103, and then to position them within the furnace as shown for assembly 121.

For pouring the converter is rotated to a position such that the lower lip of port 101 is about in the position of the dotted line 175, whereby the contents are discharged into a ladle 176, placed on a rail truck 177 below the furnace, as shown

in Fig. 7. To prevent the poured molten metal from splashing onto the tuyère trucks and tracks 128-131 inc., baffles are mounted, as at 178, 179, Fig. 7.

5 The principles of construction and operation above described with reference to Figures 1-15 inc., may of course be applied to converters of other than the circular-cylindrical configuration shown therein, for example, to spherical, ovoid, 10 or other shapes. Figures 16 and 17 illustrate schematically modifications wherein the converter assumes an oval shape in transverse section, as at 180, Fig. 16, and in which the hearths are of arcuate or bowed configuration in longitudinal section, as at 181, 182, Fig. 17. This concentrates the molten metal charge over a smaller hearth area which facilitates bessemerizing and pouring. Also with reference to Fig. 16, the outlet port 184 may be centered on the long rather than 15 the short axis of the ellipse, in which event of course the acid, basic and neutral lined portions would likewise have to be shifted 90°. This latter arrangement provides a shallower molten metal bath of increased surface area during the blow, as compared to the arrangement shown in Fig. 16.

It will be observed that in all modifications of the invention above discussed, the blow port is also employed for charging the molten metal, 20 slag forming material, etc., into the converter, and the port is also used for pouring off the slag, and the bessemerized charge, etc. During the blow, as above explained, the gaseous and other products due to the blow are likewise discharged through the port.

Fig. 18 is a schematic transverse section through a cylindrical type of converter provided with a tuyère arrangement such that the tuyères are insertable in the blow port and are independently adjustable in degree of inclination with respect to the molten metal charge. As in the constructions previously discussed, the converter is provided with oppositely disposed acid lined and basic lined portions 200, 201, between which is interposed a neutral lined zone 202 which includes the blow port 203. The converter is mounted to rotate about its cylindrical axis in the manner described with reference to the modifications previously discussed.

50 On each side of the furnace is mounted a set of tuyères connected to headers as shown generally at 204, 205. Thus unit 204 comprises upper and lower headers 206, 207, to which are respectively connected upper and lower tuyères 208, 209. These headers parallel the converter and are mounted for independent rotation about their axes and may additionally be mounted for displacement toward and away from the converter, employing for such purposes header 55 mountings generally similar to those of the tuyère and header unit of Fig. 7. By virtue of such mountings the tuyères are insertable into the converter through the blow port 203, as shown for unit 204, and may be completely withdrawn 60 therefrom as shown for unit 205, corresponding components of which bear the same numerical designations with the subscript *a* added, as for unit 204. One advantage of the arrangement is that the upper and lower tuyères 208, 209, may 65 be independently adjusted in angular inclination with respect to the molten metal bath 210, by appropriate rotative adjustment of the headers 206, 207 to which they are respectively connected.

70 It will be understood, of course, with reference to all of the converter constructions above

described; that the gaseous blast introduced into the converter through the tuyères, for effecting the "blow" may comprise either cold or pre-heated air or oxygen or other gaseous oxidizing agents and/or steam; and that any or all of such substances are embraced in the appended claims, by the expression "gaseous oxidizing fluid." Also, and as above explained, in all of the converter constructions above described, the outlet port for the "blow," may also be employed for the introduction into the converter of raw materials, such as hot metal, iron oxide, lime, etc., and that this port may also be employed for the pouring off of refined metal and/or slag, and that in the appended claims, the expression "port for charging, pouring and escape of combustion products" is understood to include these various operations, as well as the operation of effecting the "blow."

I claim:

1. A side-blow bessemer converter, comprising: a vessel of generally closed configuration having a port formed therein for charging, pouring and escape of combustion products, tuyère means adjacent said port for introducing a gaseous oxidizing fluid under pressure into said vessel, said vessel being shaped to provide a pair of hearths, disposed on opposite sides respectively of said port, acid refractory means lining one said hearth and basic refractory means lining the other said hearth, said acid and basic refractory linings being spaced apart by an intermediate zone including said port, neutral refractory means lining said intermediate zone and separating said acid and basic linings from each other, and means mounting said vessel for rotation about an axis substantially perpendicular to the axis of said port whereby a charge of molten ferrous metal may be bessermized in said hearths successively.

2. A side-blow bessemer converter, comprising: a vessel of substantially cylindrical configuration having a port for charging, pouring and escape of combustion products, formed in the cylindrical wall thereof, tuyère means adjacent said port for introducing a gaseous oxidizing fluid under pressure into said vessel, acid refractory means lining said vessel on one side of said port, and basic refractory means lining said vessel on the opposite side of said port, said acid and basic refractory linings being spaced apart by an intermediate zone including said port, neutral refractory means lining said intermediate zone, and means mounting said vessel for rotation about its cylindrical axis, whereby a charge of molten ferrous metal may be bessermized in said acid and basic lined portions successively without removing said molten metal from said converter.

3. A side-blow bessemer converter, comprising: a vessel of generally closed, hollow configuration, having a port for charging, pouring and escape of combustion products, formed therein, said vessel being shaped to provide a pair of hearths disposed on opposite sides respectively of said port, acid refractory means lining one said hearth and basic refractory means lining the other said hearth, said acid and basic refractory linings being spaced apart by an intermediate zone including said port, neutral refractory means lining said intermediate zone, tuyère openings formed in said vessel adjacent said hearths respectively, for introducing a gaseous oxidizing fluid under pressure thereto, and means mounting said vessel for rotation about

an axis substantially perpendicular to the axis of said port, whereby a charge of molten ferrous metal may be bessermized in said hearths successively, by appropriate rotation of said converter, and without removing said charge therefrom.

4. A side-blow bessemer converter, comprising: an outer metal shell of substantially cylindrical configuration having formed in the cylindrical wall thereof, a slot-like opening extending longitudinally substantially the length of said shell, said shell being provided with an acid refractory brick lining on one side of said opening, and with a basic refractory brick lining on the opposite side thereof, said acid and basic refractory linings being thereby spaced apart by an intermediate zone being lined with a neutral refractory brick, a removable plug of refractory material disposed in said opening, said plug having centrally formed therein a port for charging, pouring and escape of combustion gases, and having also formed therein on the opposite sides of said port, a series of tuyères for introducing a gaseous oxidizing fluid under pressure into said converter, and means mounting said converter for rotation about its cylindrical axis, whereby a charge of molten metal may be bessermized in said acid lined and basic lined portions successively without removing said charge from said converter.

5. A side-blow bessemer converter, comprising: an outer metal shell of cylindrical configuration having formed in the cylindrical wall thereof, a slot-like opening extending longitudinally substantially the length of said shell, said shell being provided with an acid refractory lining on one side of said opening, and with a basic refractory lining on the opposite side thereof, said acid and basic linings being thereby spaced apart by an intermediate zone including said opening, said intermediate zone being provided with a neutral refractory lining, a removable plug of refractory material disposed in said opening, said plug having centrally formed therein a port for charging, pouring, and escape of combustion gases, and having also formed therein on the opposite sides of said port, a series of tuyères for introducing a gaseous oxidizing fluid under pressure into said converter, means mounting said converter for rotation about its cylindrical axis, whereby a charge of molten metal may be bessermized in said acid lined and basic lined portions successively without removing said charge from said converter, manifold means mounted on said plug in communication with said tuyères, and means for supplying said gaseous fluid to said manifold with said converter rotated to both said acid and basic bessermizing positions, said means comprising a supply line extending axially to said converter, and a apertured bearing means journaling said supply line to said manifold thereat.

6. A side-blow bessemer converter, comprising: an outer metal shell of cylindrical configuration having formed in the cylindrical wall thereof, a slot-like opening extending longitudinally substantially the length of said shell, said shell being provided with an acid refractory lining on one side of said opening, and with a basic refractory lining on the opposite side thereof, said acid and basic refractory linings being thereby spaced apart by an intermediate zone including said opening, said intermediate zone being provided with a neutral refractory lining, a removable plug of refractory material inserted in said opening,

13

said plug having centrally formed therein, a port for charging, pouring and escape of combustion products, and having also formed therein on the opposite sides of said port, a series of tuyères for introducing a gaseous oxidizing fluid under pressure into said converter, means mounting said converter for rotation about its cylindrical axis, whereby a charge of molten metal may be bessemerized in said acid lined and basic lined portions successively without removing said charge from said converter, manifold means mounted on said plug in communication with said tuyères, and means for supplying said gaseous fluid to said manifold with said converter rotated to both said acid and basic bessemerizing positions, said means comprising a supply line extending axially to said converter, and apertured bearing means journaling said supply line to said manifold thereat, certain of said tuyères being inclined toward said acid and basic linings, respectively, for directing a portion of said gaseous fluid against the surface of the molten metal, and certain other of said tuyères being substantially parallel to the axis of said port for directing a portion of said gaseous fluid substantially parallel to said surface.

7. A side-blow bessemer converter, comprising: an outer metal shell of cylindrical configuration having formed in the cylindrical wall thereof, a slot-like opening extending longitudinally substantially the length of said shell, said shell being provided with an acid refractory lining on one side of said opening, and with a basic refractory lining on the opposite side thereof, said acid and basic refractory linings being thereby spaced apart by an intermediate zone including said opening, said intermediate zone being provided with a neutral refractory lining, a removable plug of refractory material inserted in said opening, said plug having centrally formed therein a port for charging, pouring and escape of combustion products, and having also formed therein on the opposite sides of said port, a series of tuyères for introducing a gaseous oxidizing fluid under pressure into said converter, means mounting said converter for rotation about its cylindrical axis, whereby a charge of molten metal may be bessemerized in said acid lined and basic lined portions successively without removing said charge from said converter, manifold means mounted on said plug in communication with said tuyères, means for supplying said gaseous fluid to said manifold with said converter rotated to both said acid and basic bessemerizing positions, said means comprising a supply line extending axially to said converter, and apertured bearing means journaling said supply line to said manifold thereat, a pair of stacks disposed on opposite sides of said converter, respectively, having lower openings positioned to communicate with said port with said converter rotated to said acid and basic bessemerizing positions respectively, and means displaceably mounting said stacks to permit of pouring through said port.

8. A side-blow bessemer converter, comprising: an outer metal shell of closed, hollow configuration, having a port formed therein for charging, pouring and escape of combustion products, said shell being shaped to provide a pair of hearths disposed on opposite sides respectively of said port, acid refractory means lining one said hearth and basic refractory means lining the other, said acid and basic refractory linings being spaced apart by an intermediate zone including said port, neutral refractory means lining said intermediate zone, means mounting said con-

14

verter for rotation about an axis substantially perpendicular to the axis of said port whereby upon rotation of said converter to oppositely disposed positions a charge of molten ferrous metal 5 may be bessemerized in said hearths respectively, tuyère means disposed on opposite sides of said converter respectively, and means mounting said tuyère means for insertion into and withdrawal from said converter, for injecting a gaseous oxidizing fluid under pressure therein with said converter rotated to said acid and basic bessemerizing positions, respectively.

9. A side-blow bessemer converter, comprising: an outer metal shell of closed, hollow configuration, having a port formed therein for charging, pouring and escape of combustion products, said shell being shaped to provide a pair of hearths disposed on opposite sides respectively of said port, acid refractory means lining one said hearth and basic refractory means lining the other, said acid and basic refractory linings being spaced apart by an intermediate zone including said port, neutral refractory means lining said intermediate zone, means mounting said converter for rotation about an axis substantially perpendicular to the axis of said port whereby upon rotation of said converter to oppositely disposed positions a charge of molten ferrous metal may be bessemerized in said hearths respectively, tuyère means 15 mounted on opposite sides of said converter respectively, tuyère openings in said converter adjacent said port, and means mounting said tuyère means for insertion into said openings and withdrawal therefrom, for selectively injecting a gaseous oxidizing fluid under pressure therein with said converter rotated to said acid and basic bessemerizing positions, respectively, and cooperating cam and cam lever actuating means 20 mounted on said converter shell and said tuyère mountings, respectively, for automatically inserting one said tuyère means into said port upon rotation of said converter to one said bessemerizing position and for withdrawing the same upon rotation of said converter to the opposite bessemerizing position, and for similarly inserting and withdrawing the same upon rotation of said converter to the opposite bessemerizing position, and for similarly inserting and withdrawing the same upon rotation of said converter to the opposite bessemerizing position, and for similarly inserting and withdrawing the second said tuyère means upon rotation of said converter to and from the second said bessemerizing position.

10. A side-blow bessemer converter, comprising: an outer metal shell of closed, hollow configuration, having an outlet port formed therein for escape of combustion products, said shell being shaped to provide a pair of hearths disposed on opposite sides respectively of said port, acid refractory means lining one said hearth and basic refractory means lining the other said hearth, said acid and basic refractory linings being spaced apart by an intermediate zone including said port, neutral refractory means lining said intermediate zone, means mounting said converter for rotation about an axis substantially perpendicular to the axis of said port whereby upon rotation of said converter to oppositely disposed positions a charge of molten ferrous metal may be bessemerized in said hearths respectively, tuyère means 25 rotatively mounted on opposite sides of said converter respectively, tuyère openings in said converter adjacent said port, and means automatically inserting said tuyère means, respectively, into said openings and withdrawing the same therefrom as said converter is rotated to and from said acid and basic bessemerizing positions.

positions respectively and vice versa, comprising cam means mounted on said converter and cam actuated lever means integral with said tuyère means.

11. A side-blow bessemer converter, comprising: an outer metal shell of closed, hollow configuration, having an outlet port formed therein for escape of combustion products, said shell being shaped to provide a pair of hearths disposed on opposite sides respectively of said port, acid refractory means lining one said hearth and basic refractory means lining the other, said acid and basic refractory linings being spaced apart by an intermediate zone including said port, neutral refractory means lining said intermediate zone, means mounting said converter for rotation about an axis substantially perpendicular to the axis of said port whereby upon rotation of said converter to oppositely disposed positions a charge of molten ferrous metal may be bessemerized in said hearths respectively, tuyère means disposed on opposite sides of said converter respectively, tuyère openings in said converter adjacent said port, and means rotatively and displaceably mounting said tuyère means for selective insertion into said converter through said openings for injecting a gaseous oxidizing fluid under pressure therein with said converter rotated to said acid and basic bessemerizing positions, respectively.

12. Apparatus for refining molten metal, comprising: a vessel of closed, hollow configuration, said vessel being shaped to provide two hearths, acid refractory means lining one said hearth and basic refractory means lining the other said hearth, a neutral refractory lined partitioning means separating said hearths, port means communicating with said hearths for charging, pouring and escape of combustion gases, and tuyère means adjacent said hearths for introducing therein a gaseous oxidizing fluid under pressure, and means for altering the relative levels of said hearths for causing molten metal deposited onto

one said hearth, to flow across said neutral partitioning means onto the other said hearth.

13. A side-blow bessemer converter, comprising: an outer metal shell of substantially cylindrical configuration having formed in the cylindrical wall thereof, a slot-like opening extending longitudinally substantially the length of said shell, said shell being provided with an acid refractory lining on one side of said opening, and with a basic refractory lining on the opposite side thereof, said acid and basic linings being thereby spaced apart by an intermediate zone, lined with a neutral refractory lining, a removable plug of refractory material disposed in said opening, said plug having centrally formed therein a port for charging, pouring and escape of combustion gases, and having also formed therein on opposite sides of said port, respectively, additional ports for insertion and withdrawal of tuyère means, tuyère means disposed on opposite sides of said converter, respectively, and means mounting said tuyère means for insertion into and withdrawal from said additional ports, for injecting a gaseous oxidizing fluid under pressure into said converter, with said converter rotated to said acid and basic bessemerizing positions, respectively.

REED LEWIS.
